UNITED STATES PATENT OFFICE.

JENNINGS DE WITT, OF NEW YORK, N. Y.

METHOD OF AND MEANS FOR DEINKING FIBROUS MATERIAL.

Application filed July 14, 1927. Serial No. 205,608.

This invention relates to an improved process for deinking fibrous material such as paper or the like.

The invention has particular reference to the recovery of newsprint paper. According to my improved process fibrous material of the kind used in the production of newsprint paper may be employed for that purpose and subsequently may be effectively recovered for subsequent use.

A feature of the invention relates to the effective removal of the ink and other foreign materials from the fibrous matter and the efficient utilization of the deinked material in the manufacture of usable paper.

An important object of the invention is to provide an improved process using cold water, thus reducing the cost of the process.

Another object is to avoid damaging or breaking down the fibers of the material being treated.

As an aid to an understanding of the invention reference is made to the accompanying drawings in which

Fig. 1 is a side elevation of a pump mechanism employed in the practice of the invention;

Fig. 2 is an enlarged sectional view of a portion of Fig. 1;

Figs. 3, 4 and 5 are cross-sections taken on the line 3—3, 4—4 and 5—5 of Fig. 2, respectively;

Fig. 6 is a longitudinal sectional view of a soaking and mangle tank employed in the practice of the invention;

Fig. 7 is an end elevation of the tank of Fig. 6;

Fig. 8 is a transverse section taken on the line 8—8 of Fig. 6;

Fig. 9 is a general layout of a deinking plant;

Fig. 10 is a side elevation of a modified form of the pump mechanism of Fig. 1;

Fig. 11 is an enlarged longitudinal section of a portion of Fig. 10; and

Fig. 12 is a detail view of the retaining clamp of Fig. 11.

Like reference characters denote like parts in the several figures of the drawing.

In the following description and claims, parts characteristic features and functions will be identified by specific means for convenience of expression, but they are intended to be as generic in their application to simi-

lar parts or equivalent construction as the art will permit.

Referring particularly to Fig. 1 there is shown a central pump mechanism 1 mounted on a base 10, having a pedestal 11 thereon for supporting a cylinder 12. A support 13 is secured to the base 10 apart from the pedestal 11 for supporting a guideway 14 in axial alignment with the axis of the cylinder 12. A piston head shown generally at 15 is slidably mounted within the chamber of the cylinder 12 and is actuated by a connecting rod 16 extending through the end wall, designated as at 17, of the cylinder 12. The outer end of the connecting rod 16 is pivotally connected to a pitman 18 and thus to a fly wheel 19 which is operatively connected in any suitable manner, as by a speed reduction gear to a source of power, preferably in the form of an electric motor 20.

The piston head 15 is provided with a perforated end wall 30 and a flange 31 integral therewith, snugly fitted in the bore of the cylinder 12. In the recess formed by the flange 31 there is mounted a mass of compressible material 32, preferably of sponge rubber or fiber mat material, which is held in place by means of a pair of spaced wire screens or grids 33. Each screen 33 may be formed, for example, of $\frac{1}{2}$ inch wire net. The inner grid is held in place by a sleeve 36 within the flange 31. A retaining ring 34 is screw-threaded into the flange 31 for maintaining the outer grid 33 in place. The other end of the wall of the cylinder 12 is flanged as at 35, and the end face thereof is machined to form a seat for a rotary valve shown in detail in Fig. 4.

Referring to Fig. 4, the rotary valve comprises a disk 40 having peripheral teeth as at 41 which engage a pinion 42. The disk 40 is apertured as at 43 so as to register in different positions of the disk with an inlet port 44 and an outlet port 45. The inlet port 44 communicates with a feed pipe 46. The outlet port 45 communicates with a pulp discharge pipe 56. A packing ring 47 is preferably mounted in an annular recess in the end wall of the flange 35 for effectively sealing the rotary valve against undesirable leakage. A housing 48 is secured to the flange 35 in any desired manner as by bolts such as 49, a gasket 50 being interposed to prevent undesirable leakage. The pinion 42 is secured to a shaft

51 as by being keyed thereto, the shaft 51 extending through a packing box 52 and terminating at its outer end in a hand wheel 53 having a control handle 54. A packing nut 55 serves to maintain the packing gland 52 in fixed position.

Attention is called to my copending application, Serial No. 208,727, filed July 27, 1927 as a continuation in part of the present application and in which the novel central pump is claimed.

For injecting into the interior of the cylinder 12 a supply of clean fluid, there is provided a supply pipe 60 (see Fig. 5) communicating with a conducting passage 61 drilled through the flange 35. The passageway 61 may be variably controlled by a valve 62, there being provided manual control means for the valve 62 in the form of a knurled nut 63. A packing gland 64 and packing nut 65 serve to prevent leakage through the valve 62. The other end of the interior of the cylinder 12 is of relatively enlarged internal diameter as at 66 and the chamber thus formed 25 is in communication with an outlet pipe 67, for the discharge of slush fluid. Although in the embodiment illustrated the various valves are shown as hand operated, it is understood that they may be operated automatically by means of a suitable valve cam shaft, or that some may be automatically operated and the remainder hand operated, without departure from the spirit of the invention.

Referring to Fig. 6, there is shown a single tank 70. In the form selected for illustration, the tank has a U shaped cross-section as indicated in Fig. 8, but it is understood that a round flat bottom tank, or other desired form, may be used if desired. The tank 40 is supported upon its flanged end walls as at 71 so that the bottom of the tank is spaced apart from the floor 72 upon which the tank is mounted. The bottom of the tank as indicated in Fig. 6 may be level with the floor 45 or the outlet end indicated at the right of Fig. 6 may be approximately one-half inch lower than the opposite end. The tank may be of any suitable dimension as for example approximately 16 feet long, 8 feet wide and 50 8 feet deep, it being understood that these dimensions are suggested only by way of example. There extends longitudinally of the tank a plurality of rotatable mangle shafts, designated as at 73, 74, 75, each having a plurality of arms thereon. These shafts are 55 similar in construction and the description of one will suffice for all. Each is rotatably mounted in opposed water tight journals such as 76, 77 positioned in the respective end 60 walls of the tank and there is also provided at one or more intermediate points along the shaft an additional bearing such as 78 mounted in a bracket 79 secured to the adjacent wall of the tank. Mounted on each shaft is a 65 plurality of members such as 80, each being

keyed to the respective shaft and each having a plurality of radially extending mangle arms such as 81, shown four in number, there being a relatively large number of members 80. The members 80 are disposed in spaced relation so that the mangle arms are approximately six inches apart. Each is preferably approximately 15 inches in length, and at its end is diamond pointed, so as to tear the paper apart efficiently without damage to the 75 fibers.

One end of each of the shafts extends outwardly of the tank and terminates in a sprocket wheel such as 90 (see Fig. 7). The sprockets 90 are operatively interconnected 80 by a drive chain 91 so as to be rotated simultaneously and in the same direction. One of the shafts, such as 75, is provided with a spiral gear 92 loosely mounted thereon and having a toothed hub 93 forming the driven 85 member of a clutch. A drive clutch member 94 is slidably mounted on a splined portion 95 of the shaft 75 and is grooved as at 96 for engagement with pins of pivoted arm 97. The arm 97 is provided with a handle 98 for conveniently controlling the clutch. The arrangement is such that the slideable driving member 94 rotates with the shaft 75 and when in the right-hand position shown in Fig. 6 engages the driven member 93 and 95 locks the spiral gear 92 to the shaft 75. When the driving member 94 is moved to the left of Fig. 6 by the arm 97 the spiral gear 92 is free of the shaft 75. The spiral gear 92 meshes with a gear 99 secured to a constantly 100 driven shaft 100 forming a source of power.

For injecting solution into the tank there is provided a solution pipe which may take the form of a hose 110 extending over the side wall of the tank, a supply pipe 111 controlled by valve 112, a clean fluid supply pipe 113 controlled by valve 114 and a discharge pipe 115 controlled by valve 116. The intake pipes 111, 113 communicates by way of suitable fluid tight unions with the bottom of one 110 end of the tank and the discharge pipe 115 communicates by way of a fluid tight union with the bottom of the other end of the tank.

A typical plant layout is shown diagrammatically in Fig. 9 and comprises a bank of 115 eight mangle tanks 70 similar in construction. A source of clean water 120 is connected by branch pipes 121 to the valves 114 of the tanks 70 and by way of pipe 122 and a control valve 123 to the pipe 60 of the central washing cylinder 12. The discharge control valves 116 of the tanks 70 are connected by way of branch pipes 124, 125 to the intake pipe 46 of the pump 1. The outlet pipe 67 of the pump 1 communicates with a 120 storage vat 126 for used fluid. The storage vat may be of any suitable form as for example a tank approximately 16 by 32 by 4 feet.

The pipe 67 is branched as at 135, a valve 130

136 being interposed in the branch leading to the tank 126 and a branch pipe 137, having a control valve 139 leads to a soap concentrator, forming part of a soap plant (not shown) it being understood that the soap plant also includes means for producing a supply of clean saponifous solution which may be supplied by a pipe 139 to the hose 110. The vat 126 is provided with an outlet 127 having a control valve 128 leading to a pump 129. The outlet pipe 130 extends by way of branch pipes 131, 132 to the valves 112 of the tanks 70. The pulp discharge pipe 56 extends from the cylinder 12 to a clean pulp storage tank 133 in which the clean pulp may be stored and subsequently discharged through a pipe 134 whenever desired.

In operation, a quantity of saponifous solution is injected through the hose 110 into one tank 70 until all of the mangle blades 81 of the tank are covered by the solution. The drive shaft 100 is operated but the clutches 93, 94 are left disengaged. The process will be described with reference to the arrangement illustrated in Fig. 9, it being assumed that the lower left-hand tank of this figure being the first one of the series and that the successive tanks considered in a clockwise direction are successively in that order. The printed paper to be acted upon is now deposited in the middle of the tank above the middle shaft 75 and the material is allowed to soak for approximately two hours in the saponifous solution with the clutch members 93, 94 disengaged and the shafts 73, 74, 75 idle. After this period the clutch is thrown into engagement and the mangles are operated for a period of fifteen minutes. The material is then permitted to soak for an additional interval of one hour with the clutch disengaged. The clutch is then once more engaged so that the mangle blades are again rotated for a period of three-quarters of an hour. During the last fifteen minutes of this three-quarter hour period, the valve 114 of the first tank is opened and clean water is introduced into the tank.

The first soak of two hours with the mangles idle permits the saponifous solution to remove a considerable amount of ink and surface dirt from the material being acted on. During the subsequent period of fifteen minutes the material is torn apart or shredded by the blades in order to give access to all of the fibers. During the succeeding interval of forty-five minutes the mangles are operated to wash the fibers and effectively remove the ink and other foreign material. It is during the last fifteen minutes of this interval that the material receives its first wash.

The motor 20 having been started for operating the central pump, the outlet valve 116 of the first tank is controlled to permit a measured quantity of the fluid to pass by

gravity into the pipe 46. The valve controller 54 is manipulated to permit the interior of the cylinder 12 to be filled with the solution as the piston head 15 is drawn to the left of Fig. 1, it being understood that when the inlet pipe 46 is opened to the cylinder 12 the outlet port 45 of the rotary valve 40 is closed. The inlet port 44 of the rotary valve 40 is now also closed. On the right-hand stroke of the piston 15 the sponge rubber 32 is compressed against the solution. At the beginning of the next left-hand stroke, the rotary valve 40 still remaining closed the sponge rubber or fiber mat 32 expands to the extent permitted by the screen 33. In thus expanding the sponge rubber 32 takes up considerable water, but its characteristics are such that it does not take up the fibrous material.

The piston head 15 is moved to the full extent of its stroke toward the left of Fig. 2. It will be noted that the fluid has free passage through the apertures of the end wall 30 of the piston head 15 and then through the outlet pipe 67. The piston head 15 is again moved to the right and again the compressible mass 32 is pressed into contact with the pulpy material trapped within the cylinder chamber. The water valve 63 may be opened for the introduction of clean water, and thus assist in the washing of the pulp. The sponge is again compressed and when the piston head 15 again moves to the right it absorbs considerable fluid without picking up any of the fibrous material. The piston head 15 is reciprocated in this manner as many times as desirable, preferably at least three times. On each stroke the sponge 32 is alternately compressed and expanded and thus absorbs and releases fluid. The fluid flows through the pipe 67 into the storage tank 126. Before the commencement of the last right-hand stroke of the piston head 15 the handle 54 is manipulated so as to open the discharge port 45. The pulpoous mass is thereupon ejected through the pipe 56 into the clean pulp storage tank 133 from which it is drawn off through the pipe 134 into the paper mill in which it is to be used. This action may be repeated on subsequent charges of material from the first tank 70 until that tank is empty, and then the valve 116 of that tank is closed.

The operation thus described with reference to the central pump 1 requires for paper printed in black ink approximately thirty minutes. Accordingly, the second tank 70 of the series, shown just to the right of the first tank described is filled with saponifous solution thirty minutes later than the first tank was filled, and the operation is repeated with this tank in the manner described in connection with the first tank of the series. Thus when the central chamber 12 has been emptied of the pulpoous mass received from tank No. 1 and when valve 116 of tank No. 1

is closed, valve 116 of tank No. 2 is opened and the contents of tank No. 2 are similarly acted upon in the central chamber 12.

In the same manner tank No. 3 is filled with solution thirty minutes after tank No. 2 and thus the operation can be continued in sequence. After tank No. 8 has been emptied and its contents treated the operation is continued again on tank No. 1 and so on.

After the tanks have been filled the first time the saponaceous solution contained in the storage vat 126 may be used instead of fresh solution. For this purpose the motor driven pump 129 is started, the valve 128 being opened and thus the solution is driven through the pipe 130 in the branch pipes 132, 131 and by controlling the valve 112 of the tank 70 the solution may be used successively. After having been used for a time, for instance, during two cycles of operation, the valve 136 is closed and the valve 139 opened, and the solution returned to the reconcentrator and clean solution obtained from the soap plant.

In the modified embodiment, illustrated in Figs. 10, 11 and 12, the central pump mechanism comprises a base 10, having a pedestal 11 thereon for supporting a cylinder 12. A support 150 is secured to the base 10 apart from the pedestal 11 for supporting one end of a guideway 151 in axial alignment with the axis of the cylinder 12, the other end being secured to the open end of the cylinder 12. A piston head 15 is slidably mounted within the chamber of the cylinder 12 and is actuated by a connecting rod 16 pivotally connected thereto and extending through the open end of the cylinder 12. The outer end of the connecting rod 16 is pivotally connected to a slide 152, slidably mounted on the guideway 151 and having a pin and slot connection with an operating lever 153. The lever 153 is pivoted at one end as at 154 to the base 10 and is provided at its other end with a handle 155 for convenient manual operation. The pivot 154 rests in a slotted bracket 155 so that the lever 153 can readily be dismounted therefrom.

The piston head 15 is provided with a perforated end wall 30 and a flange 31 integral therewith and snugly fitted within the bore of the cylinder 12. Within the recess formed by the flange 31 there is mounted a mass of compressible material 32 held in place by means of a pair of spaced wire grids or screens 33, each of which may be formed, for example, of $\frac{1}{2}$ inch wire net. The inner grid 33 is held in place in any desired manner as by a sleeve 36 fitted within the flange 31. A retaining ring 34 is screw-threaded into the flange 31 for maintaining the outer grid 33 in place. A separable plate 160 may be conveniently placed over the outer grid 33 and is held in place by a spring clamp 161 having arcuate ends 162

engaging the inner surface of the ring 34. A hopper 170 is mounted on the base 10 beneath the open end of the cylinder 12 and is provided with a discharge pipe 67 for the discharge of slush fluid into the tank 126 or into a soap concentrator, as previously described in connection with Fig. 9.

The operation of the mechanism shown in Figs. 10, 11 and 12 is controlled manually. At the commencement of the operation, the plate 160 and clamp 161 are removed. The outlet valve of the first tank is opened so as to permit a measured quantity of the fluid to pass by gravity into the pipe 46. The valve controller 54 (see Fig. 10) is manipulated to permit the interior of the cylinder 12 to be filled with the solution, as the handle 155 is drawn to the left of Fig. 10, it being understood that when the inlet pipe 46 is in communication with the cylinder 12, the outlet port leading to the pipe 56 is closed. The inlet port leading to the inlet pipe 46 is closed when the handle 155 has been moved to the left sufficiently to fill the cylinder 12 with solution. On the right-hand stroke of the handle 155 the piston head 15 is moved to the right and sponge rubber 32 is pressed against the solution. At the beginning of the next left-hand stroke, rotary valve still remaining closed, the sponge rubber 32 expands to the extent permitted by the screen 33. In thus expanding the sponge rubber 32 picks up considerable water but its characteristics are such that it does not take up the fibrous material.

The piston head 15 is again moved to the left of Fig. 2 and this operation repeated as has been previously described with the power driven mechanism of Fig. 1. It will be noted that as the sponge rubber 32 alternately expands and is compressed, it takes up and releases fluid from the solution, without, however, taking up the fibrous material. The fluid has free access through the end wall 30 of the piston head 15 and through the open end of the cylinder 12 into the hopper 170 and through a discharge pipe 171. Before the commencement of the last right-hand stroke of the handle 155, it is drawn fully to the left so as to move the piston head 15 out of the cylinder 12 the lever 153 being removed from its support. The plate 160 is then placed over the outer screen 33 and clamped by the clamp 161, after which the valve handle 54 is manipulated so as to open the discharge port leading to the pulp discharge pipe 56. The handle 155 is then moved to the right and the dehydrated mass is forced out through the pipe 56 and into the storage tank 123. The tanks are used in rotation as previously described in connection with the embodiment of Fig. 1.

Thus it will be seen that the material is acted upon in a continuous operation with very little labor. No hot water or heating mecha-

nism is required and thus the operation can be effected at a minimum of expense.

It will be seen that in this improved process the complicated beater machines heretofore employed in prior processes, and the power equipment required for driving the same are entirely eliminated, and this avoids injury to the fibers caused by such machines.

According to the present process the fibers 10 of the material being acted upon are not damaged to any extent by the treatment and paper of good quality can be inexpensively made from recovered pulp.

With the present process black print stock 15 can be converted to washed pulp within four hours. With rotogravure or colored newspaper the material should be soaked for an additional four to eight hours, thus making a total of from eight to twelve hours for the 20 conversion of this type of paper stock.

The invention upon which this application 25 is based is broader than the specific embodiment shown and described for the purpose of illustrating at least one of the ways in which it may be employed. The scope of the 30 invention is, therefore, to be understood as not being limited by the present specific description. I intend no limitations other than those imposed by the claims.

30 What is claimed is:—

1. The process of deinking newspaper which consists in the step of soaking the printed paper in a saponifous solution for approximately two hours, shredding the soaked 35 material in solution for approximately fifteen minutes, soaking the material at rest for approximately one hour, shredding the material for approximately thirty minutes, shredding and washing the material for approximately fifteen minutes and sponging fluid 40 matter therefrom.

2. The process of deinking newsprint paper which consists in the step of soaking the printed paper in a saponifous solution for approximately two hours, shredding the soaked 45 material in solution for approximately fifteen minutes, soaking for approximately one hour, shredding the material for approximately thirty minutes, shredding and washing the 50 material for approximately fifteen minutes, and dehydrating the material by sponging.

3. The process of deinking newspaper paper which consists in the step of soaking the printed paper in a saponifous solution for approximately two hours, shredding the soaked 55 material in solution for approximately fifteen minutes, soaking the material for approximately one hour, shredding the material for approximately thirty minutes, shredding and 60 washing the material for approximately fifteen minutes, alternately immersing and removing therefrom a spongy mass of material, and intermittently compressing the spongy mass.

4. The process of recovering used newsprint 65 paper which consists in the step of soaking the paper in a saponifous solution for approximately two hours, shredding the immersed material for approximately fifteen minutes, soaking the material at rest for approximately 70 one hour, shredding the material for approximately thirty minutes, shredding and washing the material for approximately fifteen minutes, and sponging fluid matter therefrom for approximately thirty minutes. 75

5. A process of treating printed paper stock to remove the ink and recover the pulp, comprising subjecting a quantity of the printed paper to the action of a soap solution while at rest, subjecting the mixture subsequently to 80 agitation, again soaking the material while at rest, agitating the mixture, washing the stock so treated, and sponging fluid therefrom.

6. A process of treating printed paper stock 85 to remove the ink and recover the pulp, comprising subjecting a quantity of the printed paper to the action of a soap solution while at rest, subjecting the mixture subsequently to agitation, again soaking the material while at rest, agitating the mixture, washing the stock so treated, and alternately immersing and removing a sponge until dehydrated. 90

7. A process of treating printed paper stock 95 to remove the ink and recover the pulp, comprising alternately subjecting a quantity of the printed paper to the action of a soap solution while at rest and while agitated, washing the stock so treated, and sponging fluid therefrom. 100

8. A system for the treatment of newspaper stock comprising a central pump mechanism and a plurality of mangle tanks arranged to be operatively connected thereto in sequence.

9. A system for the treatment of printed 105 paper stock comprising a central pump mechanism, a plurality of mangle tanks arranged to be operatively connected thereto in sequence, a storage tank for recovered fluid and a storage tank for treated pulp. 110

10. A process of cleaning inked paper stock and like materials which consists in immersing the material in a cold saponifous solution for a measured period of time, agitating the mixture for a measured time interval, again soaking the material while at rest, agitating the mixture and subjecting the mixture to the action of sponge rubber. 115

11. A process of cleaning inked paper stock 120 and like materials which consists in alternately subjecting the material to a saponifous solution while at rest and while agitated, and subsequently subjecting the mixture to the action of sponge rubber.

12. A process of cleaning inked paper stock 125 and like materials which consists in immersing the material in a cold saponifous solution for a measured period of time, agitating the

13. A mixture for a lesser time interval, again soaking the material while at rest, agitating the mixture, washing the material and subjecting the mixture to the action of sponge rubber.

13. A process of cleaning inked paper stock and like materials which consists in alternately subjecting the material to a saponifous so-

lution while at rest and while agitated, washing the material and subsequently subjecting the mixture to the action of sponge rubber.

10

Signed at New York in the county of New York and State of New York this 13 day of July, A. D. 1927.

JENNINGS DE WITT.
